UNITED STATES PATENT OFFICE

2,460,392

KETTLE FURNACE

Oscar R. Olson, Pittsburgh, Pa.

Application March 22, 1946, Serial No. 656,319

10 Claims. (Cl. 263—11)

1

This invention relates generally to improvements in kettle furnaces and more particularly to improvements in the method of building and in the construction of kettle furnaces to contain a heated liquid bath in which articles are immersed for heat treatment or coating.

Kettle furnaces of this character may contain salt solutions such as a Houghton salt solution that will not evaporate at elevated temperatures, or contain baths containing lead, tin or zinc, the latter of which is employed as a speiter for galvanizing the surface of the articles immersed. The salt and lead baths are employed to uniformly heat the articles for annealing or normalizing treatment.

The principal object of this invention is a novel kettle furnace construction that provides a uniform deterioration of the kettle walls, thereby prolonging the life of the kettle.

Another object is the provision of a kettle or tank furnace that is more efficient and operates with a materially less fuel input per unit tonnage of articles treated.

Another object is the provision of a sump for conveniently recovering the bath without destruction of the furnace in case the kettle bursts.

Another object is the construction of a bath-recovering sump and drain which may function without fouling the flues and do not affect the operation of the latter.

Another object is the provision of a novel construction and method of assembling the combustion chamber and flues in a kettle furnace.

Another object is the provision of novel tile construction blocks for fabricating the combustion chamber and flues of a kettle furnace.

Other objects and advantages appear in the following description and claims wherein:

Fig. 1 is a view in horizontal section of the furnace comprising this invention taken along the line 1—1 of Fig. 2.

Fig. 2 is a view in vertical section taken along the line 2—2 of Fig. 1.

Fig. 3 is an enlarged isometric view showing a portion of the tile for the construction of the furnace.

Fig. 4 is an enlarged view of a series of arched outlet ports disassociated from the furnace structure.

Fig. 5 is a sectional view of a kettle furnace having a double-decker burner in each side wall.

Fig. 6 is a perspective view illustrating the inverted pier arches which form the downtake outlets to the flues.

Referring to the drawings the furnace is built

within the pit 1 which is lined with a reinforced concrete consisting of the bottom mat 2 which extends the full length of the pit and the vertical walls 3. A moat 4 with sloping side walls is formed in the bottom of the pit along each side of the mat 2 for the full length of the pit. The buckstays 5 are anchored by embedding their lower ends in the concrete. These buckstays preferably extend upwardly above the top of the pit. A concrete partition 6 encases a portion of the outer side of each buckstay and extends across the moats 4 and connects with the side walls 3 to brace the buckstay and to divide the moats into independent compartments which are interconnected by the weirs 7 in the top of each partition 6. The side surfaces of these partition walls are also provided with a batter.

A thick insulating firebrick base 8 is laid on the top of the mat 2 and extends between the buckstays 5 which surround the central portion of the mat 2. At the location of each burner, of which there are three between adjacent buckstays, the base 8 is formed with an outwardly and downwardly sloping trough 9. Three of these lateral troughs 9 open into one of the compartments in the moats 4.

The kettle 10 is a fabricated steel open top tank with smooth welded joints and capable of holding a liquid and withstanding high temperatures. The walls of the tank extend above the pit. The aggregate capacity of the compartments of the moat 4 preferably equals the capacity of the tank 10 to enable the moat to receive the whole of the contents in case the tank bursts.

The top of the firebrick base 8 is conditioned to receive and fully support the tank 10. The combustion chambers and flues are constructed around the tank. A barrier wall 11 of firebrick tile is first laid on the base 8 surrounding the lower portion of the tank. The barrier wall and the base thus completely encase the lower portion of the tank 10 in insulating material and no openings or flues are extended through or thereunder. The top third portion of the barrier 11 recedes toward the tank wall but the bottom two-thirds of this wall is of uniform thickness. This construction of the barrier wall is important as it permits proper heating of the tank bottom through the barrier.

The space between adjacent buckstays 5 is divided into a plurality of compartments, such as three compartments of equal dimension, to provide the independent combustion chambers 12. A lateral firebrick tile pier 13 is constructed on

the base 8 to separate the lower portion of these combustion chambers 12 for the height of the barrier wall 11. The piers 13 are formed to fit against the outer face of the barrier wall 11, and they extend outwardly, one on each side of a trough 9, and stop short of the longitudinally continuous outer firebrick tile wall 14. The outer ends of adjacent piers are connected by the arched outlets 15 which with the wall 14 form the flues 16. It will be noted that the wall 14 bridges the troughs 9.

17 indicates the horizontal tile slabs which form the top wall of the flues 16 are laid with their outer portions supported on the top of the wall 14 and their inner portions resting on top of the arched outlet walls 15 and on the piers 13 with the joints of adjacent slabs 17 abutting on the center lines of the piers 13. Thus the slabs 17 form a continuous ceiling for the flues 16 and a floor for the fire beds 18.

A continuous bridge wall 19 made of firebrick tile is laid along the slabs 17 adjacent their inner edges, thereby forming a continuous trough and segregating the fire bed 18 from the outer walls of the tank 10 and exposing the latter for the full extent of the slabs 17 and the bridge wall 19. Another section of the outer firebrick tile wall shown at 20 is laid continuously along the top of the slabs 17 adjacent their outer edges to form a continuation of the outer wall 14. The tile sections forming the walls 20 have ports 21 therethrough to receive the burners 22. Each burner is constructed to receive the combustible fuel mixture from a suitable distributing source and direct it downwardly into the fire beds 18, which beds are made of suitable refractory material to maintain combustion and aid in heating the unburned gases before they pass upwardly to the combustion chambers 12.

The fuel beds 18 of each burner are open continuously to each other in the same manner as the flues 16. The upper portion of the bridge walls 19, which face the tank 10, are made to recede as indicated at 23 to permit the burning gases to flow without restriction through the downturnake 24 in front of the bridge walls 19, where the gases are divided by the piers 13 and flow through the respective outlet openings 15 to the flue 16. The exposed tops of the piers 13 may be pointed as shown at 25 in Fig. 3 to facilitate the flow of the gases to the flues.

At each buckstay 5 a partition wall 26 extends from the outermost firebrick wall 27 to the tank 10 to shore the wall of the tank from the level of the top of the bridge wall 19 to the roof slabs 28. Intermediate of the partition walls 26 two partition walls 30 are employed to support the roof slabs 28 and segregate the combustion chambers 12 for each burner, of which there are three between adjacent side buckstays. The partitions 30 also extend to the outermost wall 27. Thus the partition walls 26 and 30 interrupt the firebrick tile wall 31 which forms an upward continuation of the wall sections 14 and 20.

The roof slabs 28 extend over and rest on the tops of the walls 27 and 31 and abut against the upper portion of the outer wall of the tank 10 below its upper reinforcing rib or lip 32. A slab of insulating material 33 is placed on the top of the slabs 28 to thermally seal them. 34 indicates 70 bracing angle iron employed to lock the outer edges of the slabs 28 in alignment within the encircling buckstays.

A grating 35 may be supported between the pit wall 3 and the buckstays 5 to prevent acci-

dents due to the open moats 4 and to provide access to the open tank 10.

5 Outwardly opening cast iron flap doors 36, hinged at the top, close the troughs 9 that run out under the outermost walls 27 to prevent leakage of air into the flues 16.

10 A chain 37 is hooked on the wall 3 and permitted to lie in the bottom of each compartment of the moats 4. Thus if the tank were to burst when containing lead, zinc or tin, the metal will flow down over the barrier wall 11 into the trough or troughs 9 and out through the flap doors 36 into the compartments of one or both moats 4. When one moat compartment fails it is permitted to flow to adjacent compartments through the weirs 7 which are subsequently broken after solidification and the slabs of metal are raised by means of the chains 37 and the material thereof re-used. The troughs 9 being 20 lower than the flue 15 prevent the metal from fouling the refractory structure and the broken tank may be removed bodily and replaced without rebuilding the furnace.

25 The flues 16 on each side of the furnace connect with an extension flue 38 which is connected to the stack 39.

The longitudinally disposed arched outlets 15 as shown in Figs. 2 and 3 form an important part of this invention. The manner in which said arch 30 outlets are constructed is as follows: An arch tile member such as shown at 40 in Fig. 4 which when built into the furnace under the slabs 17 may be laid directly on the base 8 with the tile filler members 41, 42, 43 and 44 laid on top thereof to completely fill in the gap between the tile 40 and the slab 17. Assuming that the furnace is provided 35 with fifteen burners on each side thereof, the first three burner sections adjacent the stack 39 would be laid in this manner to restrict the flow 40 of gases at this end of the furnace and prevent the flames from short-circuiting longitudinally of the downturnake 24. The next three burners would then have the short or leg tiles 45 placed 45 on the base 8 and the arched tile 40 cemented thereon and only the long tiles 41, 42 and 43 would be required on top thereof to fill in the gap.

The third series of three burner sections would 50 then have two short or leg tile sections 45 and 46 with only two filler tiles 41 and 42 on top of the arched tile 40. The fourth series has three short or leg tiles 45, 46 and 47 and one long filler tile 41 on top, whereas the fifth or last series of three burner sections, which are remote of the stack, have only the short or leg tiles 45, 46, 47 and 48 55 and no filler tiles on the top of the arched tile 40.

In this manner the restricted outlets 15 from the combustion chambers 12 to the flues 16 are graduated to produce a uniform pressure distribution throughout the combustion chambers, thereby providing a uniform distribution of the burning gases even though the fire beds 18 and the downturnakes 24 are open to each other for the full length of the furnace.

With this construction substantially half of 65 the walls of the tank 10 adjacent the combustion chambers 12 is exposed to the burning gases and the fuel is provided to supply a maximum of B.t.u.'s per square foot exposed per hour. This fuel consumption rate will maintain a lead bath at 1600° F. The firing rate is reduced for the different characters of baths. Thus a Houghton salt bath is maintained at 900° F., a zinc bath at 850° F. and a tin bath at 600° F. The temperature of the bath is measured by thermocycles 70 which are used for regulating the fuel input by

systems commonly known in the furnace heating art. The fire beds 18 and the downtakes 24 being directly connected provide an even distribution of the heat on the tank and prevent the formation of localized hot spots which ordinarily cause tanks of this character to become burned and rupture prematurely.

The double-decker burner arrangement shown in Fig. 5 is constructed in the same manner as the furnace with a single row of burners on each side as shown in Figs. 1 and 2. However the piers 13 and outlet arches 15 are replaced by the inverted arch members 50. Each inverted arch member comprises the upwardly projecting legs 51 and 52 which produce the opening or orifice 53 therebetween. When inverted as shown the bridge portion 54 of the arch slopes from the barrier wall 11 as shown at 55 to convey the bath from a bursted tank to the open trough 9. The inverted arch member 50 is preferably made of tile and it is as long as the distance between the centers of the burners to enable the legs of adjacent tile to replace the pier 13. Where the tile slabs 17 meet at the center line of the piers 13 in the structure of Figs. 1 to 3, in Fig. 5 the legs 51 and 52 support their respective slab 17.

The openings 53 of the inverted arch members 50 become increasingly larger as they progress from the stack end of the flue 16 to produce an even draft on the downtake and prevent the burning fuel from taking a short-circuiting path.

The partitions 30 may be shorter to reduce the size of the combustion chambers 12 as the burners 22 are preferably of less capacity than the upper row of burners 56. The slabs 57 are supported by the wall 20 and the partitions 30 and provide the ceiling for the combustion chambers 12 and the floor for the fuel beds 58 which are open to one another for the full length of the furnace in the same manner as that of the fuel beds 18. The bridge wall 60 is supported by the slabs 57 and in turn supports the lateral combustion chamber partitions 61 with the aid of the furnace wall 62. The wall section 62 also supports the wall section 63 and all of these wall sections are tied in with the outer wall 27. The roof 28 is supported by the furnace side walls and the partitions 61 and close the top of the combustion chambers 64.

The burning gases from the combustion chamber 64 flow through the downtake in front of the bridge wall 60 and are reheated by the additional burning fuel from the combustion chamber 12 and they continue down the downtake and flow through the outlets 53 produced by the inverted arch members 50 to the flue 16 and thence to the end of the furnace and on to the stack. Proper damper means are provided to regulate the draft.

With this double-decker burner arrangement a much deeper tank 10 may be properly heated and the very bottom of the tank is properly shielded from intense heat to prevent agitation of the precipitant in both structures.

I claim:

1. In a kettle furnace the combination of a mat having a flat continuous surface, an open top tank supported on the mat, furnace end walls covering the end of the tank, a relatively low barrier wall on the mat along each side of the tank for boxing in the bottom thereof, furnace side walls connecting the end walls and spaced outwardly from the barrier walls, a row of fuel burners in each furnace side wall, a series of spaced piers extending laterally from each barrier wall but stopping short from their respective

furnace side wall to provide a longitudinal flue space, a slab supported by the outer ends of the piers and the furnace side walls below the burners to form a ceiling for the flues and a fuel bed floor for the burners, an upwardly projecting bridge wall along the inner edge of the slabs and spaced from the tank to shield it from the fire beds and to provide a downtake to the outlets between the piers to the flues, and a roof supported above the bridge walls to provide combustion chambers connecting the fire beds with the downtake.

2. The structure of claim 1 which also includes spaced lateral partitions supported on the bridge walls to partition off portions of the combustion chambers for each burner and aid in supporting the roofs.

3. The structure of claim 1 which also includes spaced lateral partitions supported on the bridge walls to partition off portions of the combustion chambers for each burner and aid in supporting said roofs, and characterized in that said piers are aligned with said partitions.

4. The structure of claim 1 which also includes spaced lateral partitions supported on the bridge walls to partition off portions of the combustion chambers for each burner and aid in supporting said roofs, and characterized in that said piers are aligned with said partitions and certain of said lateral partitions extending from the wall of the tank to the furnace side wall.

5. In a kettle furnace the combination of a mat having a flat continuous surface, an open top tank supported on the mat, furnace end walls covering the end of the tank, a relatively low barrier wall on the mat along each side of the tank for boxing in the bottom thereof, furnace side walls connecting the end walls and spaced outwardly from the barrier walls, a row of fuel burners in each furnace side wall, a series of spaced piers extending laterally from each barrier wall but stopping short from their respective furnace side wall to provide a longitudinal flue space, a slab supported by the outer ends of the piers and the furnace side walls below the burners to form a ceiling for the flues and a fuel bed floor for the burners, an upwardly projecting bridge wall along the inner edge of the slabs and spaced from the tank to shield it from the fire beds and to provide a downtake to the outlets between the piers to the flues, a roof supported above the bridge walls to provide combustion chambers connecting the fire beds with the downtake, a stack adjacent one end of the furnace, means connecting the ends of the flues to said stack, and means between adjacent piers to restrict the outlets progressively toward the stack end of the furnace.

6. In a kettle furnace the combination of a mat having a flat continuous surface, an open top tank supported on the mat, furnace end walls covering the end of the tank, a relatively low barrier wall on the mat along each side of the tank for boxing in the bottom thereof, furnace side walls connecting the end walls and spaced outwardly from the barrier walls, a row of fuel burners in each furnace side wall, a series of spaced piers extending laterally from each barrier wall but stopping short from their respective furnace side wall to provide a longitudinal flue space, a slab supported by the outer ends of the piers and the furnace side walls below the burners to form a ceiling for the flues and a fuel bed floor for the burners, an upwardly projecting bridge wall along the inner edge of the slabs and spaced from the tank to shield it from the

fire beds and to provide a downtake to the outlets between the piers to the flues, a roof supported above the bridge walls to provide combustion chambers connecting the fire beds with the downtake, a stack adjacent one end of the furnace, means connecting the ends of the flues to said stack, and arch means between adjacent piers to restrict said outlets progressively toward the stack end of the furnace.

7. In a double-decker fired open top kettle furnace the combination of a mat, an open top tank supported on the mat, furnace end walls supported on the mat and covering the ends of the tank and extending therebeyond, furnace side walls supported on the mat and spaced from the sides of the tank and connected to the end walls, parallel rows of spaced fuel burners in each furnace side wall, a plurality of laterally extending piers extending from the tank but spaced from the side walls to provide a longitudinal flue space, a slab supported by the piers and the furnace side walls below the lowest row of burners but having its inner edge spaced from the tank, an upwardly projecting bridge wall along the inner edge of the slabs to shield the tank from direct impingement of the flames and provide a downtake between the piers to the flues, a second slab supported above said bridge walls and below the upper row of burners to form a combustion chamber ceiling for the lower burners but having its inner edge spaced from the tank, another upwardly projecting bridge wall along the inner edge of the second slabs to shield the tank from direct impingement of the flames and to extend the downtake between the piers, and a roof supported above the upper bridge walls to enclose the furnace.

8. The structure of claim 7 which also includes spaced lateral partitions supported by the furnace side walls and each of the bridge walls to partition off portions of the combustion chambers for each burner, the lower partitions supporting the upper slabs and the upper partitions supporting said roofs.

9. The structure of claim 7 characterized in that said piers are constructed from the legs of an inverted arch and the passages produced thereby form the outlets of the downtakes to the flues.

10. The structure of claim 7 characterized in that said piers are constructed from the legs of adjacent inverted arches, the orifices of said arches being progressively larger from the discharge end of the flue to the other end of the furnace.
